UNITED STATES PATENT OFFICE.

WILLIAM D. DREISKE, OF CHICAGO, ILLINOIS.

COMBINED WINDOW LOCK AND ADJUSTER.

1,104,973.

Specification of Letters Patent. Patented July 28, 1914.

Application filed October 20, 1913. Serial No. 796,201.

To all whom it may concern:

Be it known that I, WILLIAM D. DREISKE, a citizen of the United States of America, and resident of Chicago, Cook county, Illinois, have invented a certain new and useful Improvement in Combined Window Locks and Adjusters, of which the following is a specification.

My invention relates to casement windows, doors, etc., having devices for holding the same in either open or closed position.

Generally stated, the object of my invention is to provide a novel and satisfactory device or fixture for this purpose.

A special object is to provide a locking device of this kind which will not only hold the window in open or closed position, but which will also lock the sash at both ends thereof, as at top and bottom of a casement window, and to thereby provide a combined window lock and adjusting device. In this way, and by employing a single mechanism having both of these functions, I obviate the necessity for more than one fixture for each window, as in this way, it will be seen, the locking of the bottom of the swinging sash of a casement window serves also to lock the top thereof, thus rendering a separate locking operation unnecessary.

It is also an object to provide certain details and features of construction tending to increase the general efficiency of a casement window fixture, or combined locking and adjusting device, of this particular character.

To these and other useful ends, my invention consists in matters hereinafter set forth and claimed.

In the accompanying drawings—Figure 1 is an inside elevation of a casement window having a combined locking and adjusting device embodying the principles of my invention. Fig. 2 is a vertical section on line 2—2 in Fig. 1. Fig. 3 is a horizontal section on line 3—3 in Fig. 1, showing the window open. Fig. 4 is a similar view showing the window only slightly open. Fig. 5 is a perspective of the hook shaped end portion of the handle by which the mechanism is operated, and by which the swinging sash is held in either open or closed position. Figs. 6, 7, 8, 9 and 10 are views similar to Figs. 1, 2, 3, 4 and 5, respectively, showing another form of my invention.

As thus illustrated, and referring to Figs. 1 to 5 inclusive, the window frame A may

be of any suitable construction. The sash B is hinged at b to swing outward. A vertically disposed rod C is mounted in bearings c and c¹, adjacent the free side of the sash, and is formed with upper and lower arms c² and c³, the latter being extended to form a handle c⁴ for operating the mechanism. Upper and lower pins D and E are mounted on the window frame A, adjacent the corners of the sash, and in position to engage the arms c² and c³, when the window is closed and the handle swung toward the sash. This draws the sash tightly to the frame, and the hook portion c⁵ is then sprung upward and behind the pin F on the window sill. Preferably the handle c⁴ is bent upwardly to pass over the pin E in opening the window. To hold the window open the eye c⁶ of the handle is engaged with the pin E, as shown in Fig. 3. But to hold the window only slightly open, the said eye is engaged with the pin F, as shown in Fig. 4. Thus the locking of the bottom of the window serves also to lock the top thereof. In addition the handle of the mechanism is operative to hold the window open, and to adjust the sash to different positions.

In Figs. 6 to 10 the construction involves a vertical rod G on the frame H, having upper and lower arms g and g¹, disposed adjacent the corners of the sash I, the rod being mounted in bearings g² and g³ secured to said frame. In this case, however, the sash swings inward, instead of outward, and the handle g⁴ engages a pin or other element g⁵ on the sash, when the window is closed. In this position the arms g and g¹ engage the plates g⁶ and g⁷ to crowd the sash tightly into position to close the window. When the window is open, the handle eye g⁸ is engaged with either of the pins g⁹ or g¹⁰, which latter are secured to the outside of the sash. Thus the sash is held in either partially or fully opened position.

In each form of my invention the window is locked at top and bottom by one and the same operation. The handle not only locks the window sash in either open or closed position, but also serves to operate the upper locking device. Thus only one fixture or mechanism is necessary for each sash.

In both forms of my invention, it will be seen, the locking arms, and also the handle, are integral with the rod. As shown, the rod is simply bent into the desired shape, and thus the securing together of separate

parts is avoided. Obviously, however, the said locking arms and handle can be formed or provided in any suitable manner.

In each form of my invention the rod is 5 of elastic material, such as hard brass or steel, whereby the handle may be sprung into position to hold the sash in closed position, without permanently bending the same. Thus the handle and the rod are under tension when the window is locked.

What I claim as my invention is:—

1. A casement window provided with a swinging sash, and mechanism for holding the window sash in either open or closed 15 position, comprising a rod mounted to rotate on the window, provided with locking arms disposed adjacent the corners of the sash, one of said arms being extended to form a handle, said handle having engagement with 20 the window to lock the sash in closed position, and to hold the window open.

2. A casement window provided with a swinging sash, and mechanism for holding the window sash in either open or closed 25 position, comprising a rod mounted to rotate on the window, provided with locking arms disposed adjacent the corners of the sash, one of said arms being extended to form a handle, said handle having engagement 30 with the window to lock the sash in closed position, and to hold the window open, said arms having locking engagement with the window, to firmly close the sash, and said handle being movable toward the 35 sash to close and lock the same.

3. A casement window provided with a swinging sash, and mechanism for holding the window sash in either open or closed position, comprising a rod mounted to 40 rotate on the window, provided with locking arms disposed adjacent the corners of the sash, one of said arms being extended to form a handle, said handle having engage-

ment with the window to lock the sash in closed position, and hold the window open, 45 the said rod extending parallel with the free edge of the sash, bearings for said rod, disposed between said arms, and a plurality of devices on the window, serving to provide the means of said engagement with the 50 handle.

4. A casement window provided with a swinging sash, and mechanism for holding the window sash in either open or closed position, comprising a rod mounted to rotate 55 on the window, provided with locking arms disposed adjacent the corners of the sash, one of said arms being extended to form a handle, said handle having engagement with the window to lock the sash in 60 closed position, and to hold the window open, the said rod extending up and down, and said handle being movable in a horizontally disposed plane at the bottom of the window.

5. A casement window provided with a swinging sash, and mechanism for holding the window sash in either open or closed position, comprising a rod mounted to rotate 65 on the window, provided with locking arms disposed adjacent the corners of the sash, one of said arms being extended to form a handle, said handle having engagement with the window to lock the sash in closed position, and to hold the window 75 open, said handle having a hook with an eye in the end portion thereof, and means on the window for engaging the said hook, adapted to enter said eye.

Signed by me at Chicago, Illinois, this 80
11th day of October, 1913.

WILLIAM D. DREISKE.
